UNITED STATES PATENT OFFICE.

JOHN C. VAN AKEN, OF RIDGWAY, PENNSYLVANIA.

FLOWER-HOLDING AND GRAVE-COVERING DEVICE.

No. 919,655.

Specification of Letters Patent.

Patented April 27, 1909.

Application filed October 3, 1908. Serial No. 455,957.

To all whom it may concern:

Be it known that I, JOHN C. VAN AKEN, a citizen of the United States, residing at Ridgway, in the county of Elk and State of Pennsylvania, have invented or discovered certain new and useful Improvements in Flower-Holding and Grave-Covering Devices, of which the following is a specification, reference being had therein to the accompanying drawings.

This invention has for its object to provide a flower-holding and grave-covering device of such a character as to be conveniently transported, and which is of such construction that it may be connected with the straps by which a casket is lowered into a grave in such a manner that as the casket descends the flower-holding device, with its burden of floral decorations, will be automatically moved into position to cover the open grave, and in which position it may be left during the concluding funeral exercises and until the family and friends have departed and the grave is to be filled.

To this end the invention comprises a foldable frame-work including tracks on which a flower-holding and grave-covering carriage may run, and which frame-work, when in operative position, will preferably be partly supported by a casket-lowering device such as is in common use, and partly by suitable standards detachably or foldably connected with the said frame-work, the flower-holding and grave-covering carriage being preferably made extensible and contractible, so that it may be adjusted to a collapsed or contracted condition for convenient transportation, suitable flexible connections being provided whereby the carriage may be connected to the straps of the casket lowering device, so that as the casket is lowered the flower-bearing carriage will be automatically moved to a position to cover the open grave, all as will be hereinafter more fully set forth.

In the accompanying drawings Figure 1 is a perspective view of the invention, illustrative of the operation thereof. Fig. 2 is a partial longitudinal section of the frame of the apparatus, with the flower-holding carriage in transverse section. Fig. 3 is a transverse section of the portion of the frame-work providing tracks for the flower-holding carriage which is shown in side elevation in position on the said tracks. Fig. 4 is a detail view showing one-half of the two-part frame in

folded condition convenient for transportation.

Referring to the drawings, 12 denotes a casket-lowering device, which may be of any ordinary or well-known construction, and which is usually in the form of a rectangular frame provided with straps 13 which may, if desired, be placed under tension by any suitable friction devices. The lowering device is usually supported by benches 14 at a convenient height over the grave excavation, as shown in Fig. 1.

The present invention comprises a folding frame-work which, as herein shown, consists of two disconnectable parts each of which comprises two slotted end pieces 15, and two grooved side pieces 16 connected together by hinges 17 and pivotally connected with the said end pieces 15 by thumb nut bolts 18, the said end pieces being detachably and adjustably connected together by thumb nut bolts 19. This construction is such that the two parts constituting the frame-work or support for the flower-holding and grave-closing carriage may be disconnected from each other and may each be folded for convenient transportation as shown in Fig. 4; but when extended into position for use the said frame-work may be supported at one end by simply resting on the lowering device 12, or by being temporarily attached thereto by means of cords or straps 20, while the opposite end of said frame-work will preferably be supported and steadied by slotted legs or standards 21 attached to the frame-work by thumb nut bolts 22. If desired, suitable pegs, as 23, to be partly driven into the ground, may be connected with the said frame-work by steadyng chains 24 or other suitable flexible connections.

The flower-holding and grave-covering carriage comprises a suitable contractible and extensible frame-work which is herein shown as consisting of two slotted side pieces 25 and two slotted end pieces 26 which are capable of adjustment in or out, and which may be secured in any desired position of adjustment by means of thumb nut bolts 27. The top or flower-supporting part or platform of the carriage will preferably comprise a series of metal tubes 28 each of which is flattened at one end and attached to a side bar of the carriage, and a series of metal rods 29 fitting in said tubes and also having flattened outer end portions attached to the op-

95

110

posite side bars of the carriage, so that in contracting or extending the carriage laterally the rods can slide in said tubes telescopically; while in contracting or extending the frame-work of the carriage longitudinally one series of said rods and tubes on one part of the carriage frame can slide over the similar series of rods and tubes on the other part of the carriage frame, as will be understood by reference to Figs. 1 and 2. The carriage is provided with suitable legs 30 each furnished with a wheel 31 adapted to run in or on the tracks afforded by the foldable side pieces 16 of the supporting frame, said side pieces 15 being preferably grooved to receive said wheels.

While the contractible and extensible carriage preferably comprises the telescopically adjustable tubes and rods above referred to, it will be understood that any suitable equivalent, as canvas or other fabric, and which will properly support the floral pieces, might be employed instead of the said rods and tubes; and it will also be understood that the said rods and tubes, constituting the flower support or platform of the carriage, may (and preferably will) be covered by canvas or other suitable fabric when in use.

The side and end pieces 25 and 26 of the adjustable carriage, and also the end pieces 15, of the adjustable frame, will preferably be provided with gage marks, as shown, for convenience in uniformly adjusting two opposite parts of said carriage and frame.

The operation of the invention will readily be understood from the foregoing. In transporting the apparatus to a cemetery the carriage will preferably be contracted to the smallest possible compass by sliding the end and side pieces thereof as near together as possible, and the two parts of the portable frame will at such time be disconnected from each other, and will each be folded up with the parts parallel to each other, as shown in Fig. 4; but when the apparatus is to be put into use the frame-work will be extended and secured together as shown in Fig. 1, and the carriage will be likewise extended to correspond to the frame-work by which it is supported, and on which it is adapted to run. Of course it will be understood that both the carriage and its supporting frame-work, in being adjusted for use, will be extended in accordance with the size of the grave excavation which is to be covered. When the casket which is to be lowered into the grave is first placed in position it will be supported on the lowering device 12, and at this time the carriage bearing the floral decorations will be run back on its supporting frame a suitable distance and will be connected with the casket lowering straps 13 preferably by means of wire cords 32, such connections being preferably made by suitable hooks 33 at one end which can be engaged with the slots

at the rear side of the carriage, and which wire cords may be connected with the lowering straps 13 at their other ends by similar hooks, and which may, if desired, be sharpened for engagement with said straps. Thus when a casket, as 34, is being lowered, and the straps 13 are drawn downward, the flower-holding carriage will be automatically drawn forward so that when the casket has descended to the bottom of the grave the said carriage with its floral decorations will be over the lowering device 12, and will thus serve to cover and hide the grave from view. To this end it will be understood that the flower-holding carriage will preferably be so extended as to have a considerable larger area than the grave, so that even if the lowering device be placed in a position some little distance above the ground the open grave will still be hidden by the flower-holding device. The quiet automatic movement of the flower-holding and grave-closing device to its grave-covering position, as the casket is lowered, will add considerably to the impressiveness of the ceremonies.

The invention is not to be understood as being limited to the details herein shown, as such details may be varied considerably, within the province of mechanical skill, without departing from the spirit of the invention; although the best form thereof, so far as is at present known, is herein shown and described.

Having thus described my invention I claim and desire to secure by Letters Patent:—

1. A flower-holding and grave-covering device consisting of a frame-work comprising suitable tracks, a carriage provided with wheels to run on said tracks, and means for connecting said carriage with the casket-lowering straps, so that as the casket is lowered the flower-bearing carriage will be automatically moved to a position to cover the grave.

2. A flower-holding and grave-covering device consisting of an adjustable and foldable frame-work comprising suitable tracks, a contractible and extensible carriage provided with wheels fitted to said tracks, and means for connecting said carriage with the casket-lowering straps, so that as the casket is lowered the flower-bearing carriage will be automatically moved to a position to cover the grave.

3. A flower-holding and grave-covering device comprising an adjustable and foldable frame-work consisting of two detachable parts each of which includes four pieces jointed together so that they may be folded parallel to each other and two of which pieces are constructed to afford foldable tracks, combined with a carriage provided with wheels fitted to run on said tracks.

4. A flower-holding and grave-covering device comprising an adjustable and foldable

frame-work consisting of two detachable parts each of which includes four pieces jointed together so that they may be folded parallel to each other and two of which pieces are constructed to afford foldable tracks, combined with a contractible and extensible flower-bearing carriage provided with wheels fitted to run on said tracks.

5. A flower-holding and grave-covering device comprising a suitable supporting frame having tracks, combined with a contractible and extensible flower-holding carriage fitted to run on said tracks and the top or platform part of which is composed of 10 telescopically adjustable rods and tubes, the former fitting in the latter, and attached at 15 their ends to the side-bars of the carriage.

6. A flower-holding and grave-covering device consisting of an adjustable and foldable frame-work comprising suitable tracks, 20 combined with a contractible and extensible flower-bearing and grave-covering carriage fitted to run on said tracks and the upper or 25 platform part of which is composed of a series of metal tubes attached to one side-bar

of the carriage and a series of metal rods attached to an opposite side bar of the carriage and fitting telescopically in said tubes.

7. A flower-holding and grave-covering device consisting of an adjustable and foldable frame-work comprising suitable tracks, combined with a contractible and extensible flower-bearing and grave-covering carriage fitted to run on said tracks and the upper or 30 platform part of which is composed of a series of metal tubes attached to one side-bar of the carriage and a series of metal rods attached to an opposite side bar of the carriage and fitting telescopically in said tubes, and means for connecting said carriage with 35 the casket-lowering straps, so that as the casket is lowered the said carriage will be automatically moved to a position to cover the grave opening.

In testimony whereof I affix my signature, 40 in presence of two witnesses.

JOHN C. VAN AKEN.
